UNITED STATES PATENT OFFICE.

HARRY S. GORE, OF MIDWEST, WYOMING.

GRAPPLE.

Application filed January 28, 1925. Serial No. 5,277.

To all whom it may concern:

Be it known that I, HARRY S. GORE, a citizen of the United States, residing at Midwest, in the county of Natrona and State of Wyoming, have invented certain new and useful Improvements in Grapples, of which the following is a specification.

This invention pertains to grapples and by the present design it is sought to provide a simple yet rugged grapple intended primarily to be used for removing broken sucker rods from well casings.

It is also contemplated that the invention may be embodied in numerous forms to adapt it to other analogous uses, among which may be mentioned the recovery of drill bits, wire line, rope sockets and other accessories used in well drilling. For these purposes the device will take the form of a fishing tool. In a modified form of the invention, hereinafter described, the device is made in the form of a spear for pulling out well casings or recovering parted or lost pipe.

Tools of this general character heretofore devised have numerous shortcomings, principal of which are inability to stand the great strains to which they are subjected, complicated constructions resulting in disuse of the tools when once out of repair, and inefficiency of operation.

The present invention is intended to overcome these objections by furnishing a tool which is extremely simple in both construction and operation, in which the number of parts is reduced to a minimum and the parts are all of such construction that there is small chance of breakage.

A further object is a device which may be readily dismounted and assembled to replace broken or worn parts.

Referring to the accompanying drawings, wherein like reference numerals designate the same parts throughout the several views, there are shown two practical embodiments of the invention, one, a fishing tool, and the other, a casing spear.

Fig. 1 represents a front elevation of the fishing tool suspended in a well casing (shown in section) and about to engage the upper end of a broken sucker rod;

Fig. 2, a sectional view of the same tool with the parts in the positions which they assume as the tool comes into partial engagement with the sucker rod;

Fig. 3, a similar sectional view, fragmen-

tary, of the tool in full engagement with the sucker rod and ready to be elevated to carry the rod with it;

Fig. 4, a section taken on line 4—4 of Fig. 3 looking upwardly, showing the cross-sectional shape of the slips of the tool at this point and illustrating in dot-and-dash lines the manner in which they may be removed from the fulcrum ring;

Fig. 5, an inside elevational view of one of the slips removed from the tool; and

Fig. 6, a sectional view of a casing or pipe spear embodying the invention, the spear being shown in operative engagement with the casing as when the latter is being drawn from the well.

In the drawings, except Fig. 6, 1 is the well casing in the lower portion of which rests the broken sucker rod 2. In order to adapt the present tool for recovering sucker rod 2 or other object from the lower end of the casing, it is made up of a series of metal slips 3 held in proper assembled relation to each other and the rest of the tool by means of a fulcrum ring 4. Three slips 3 are used in the present construction as this has been found to be the most efficient number, although it is to be understood that any number, from two up, may be used if found advisable. Each slip 3 is provided externally with a transverse groove 5 in which a portion of the fulcrum ring 4 rests. Fulcrum ring 4 is of such size as to fit loosely in the grooves 5 in the slips, so as to permit of the pivotal movement of the slips hereinafter described.

Upon reference to Fig. 4, it will be seen that each slip 3 is of segmental form in horizontal cross-section and of such size as to permit it to pivot or swing vertically on fulcrum ring 4 when assembled with the other slips.

Slips 3 are shaped so that when assembled and resting with their lower edges on a flat surface, the lower portion of the tool is practically cylindrical, while the upper part of the tool, that is, the part above fulcrum ring 4, tapers somewhat inwardly and upwardly. The purpose of this will appear later.

Interiorly each slip 3 is formed with an inwardly and downwardly inclined surface 6 extending from the upper edge of the slip and merging at its lower edge with an outwardly and downwardly inclined surface 7. These two inclined surfaces 6 and 7 at their juncture form a ridge 8 which may be round-

ed off if desired. Projecting between the upper portions of the several slips 3 is a rod 9 having a downwardly and outwardly flaring enlargement or head 10 formed on the lower end thereof. Rod 9 comprises the means for raising and lowering the tool in the casing 1.

Slips 3 are also each provided interiorly with an inwardly projecting, horizontal rib 11 adapted to serve as an abutment for head 10 of rod 9 and also to re-enforce the slips at this point, perhaps the greatest point, of strain when the tool is being used to lift an object.

The head 10 on rod 9 is adapted to spread open the upper ends of slips 3 and to accomplish this it is made sufficiently large, so that when the tool is suspended by rod 9, ridges 8 of the several slips 3 will gravitate into engagement with the inclined surface of the head, thereby rotating each of the slips about fulcrum ring 4 as a center. This results in the lower portions of the slips swinging inwardly until their edges abut at the lower ends thereof. In other words, when the tool is suspended by rod 9, the parts gravitate so as to cause an expansion of the upper part of the tool and a contraction of the lower part thereof, as clearly shown in Fig. 1.

The lower edge of each slip 3 is inclined inwardly and upwardly as shown at 12 to facilitate the engagement of the tool with the object to be lifted. Above this inclined surface 12 and extending almost to rib 11, the slip is of substantially uniform thickness and on its inner surface is formed with a series of transverse serrations 13. These serrations extend from one edge of the slip to the other and afford positive means for engagement of the tool with the sucker rod or other object 2.

In use, the fishing tool of Figs. 1 to 5, inclusive, is lowered into casing 1, as shown in Fig. 1, for the purpose of recovering the sucker rod 2. As the tool is lowered from the position of Fig. 1, in which position the lower end of the tool is contracted, it comes into engagement with the upper end of sucker rod 2. If the upper end of rod 2 should be located in the casing as shown in Fig. 1, that is, centrally thereof, it will pass readily between the lower ends of slips 3 and into the object-engaging chamber 14 as the tool is lowered, as shown in Fig. 3, being aided in this connection by the inclined surfaces 12 on the lower edges of slips 3, as shown in Fig. 2. The size and shape of head 10 on rod 9 is such, it will be understood, that, as soon as the downward movement of the slips 3 is impeded by their engagement with the sucker rod 2, head 10 will move downwardly out of engagement with the slips 3, thus permitting sucker rod 2 to pry open the lower end of the tool and enter the gripping chamber 14.

Should sucker rod 2 be disposed in the casing with its upper end close to the wall of the casing, it may still be engaged by the tool to bring it into the object-engaging chamber 14. As clearly disclosed in Fig. 2, the upper part of the tool, that is, the part above fulcrum ring 4, tapers upwardly towards the top of the tool. Rod 9, by reason of the particular construction and arrangement of head 10 and slips 3, is universally connected to the tool proper, inclined surfaces 6 on the slips 3 permitting rod 9 and the tool to assume various angular relations to each other. These features of construction, it will be seen, allow the rod 9 to be manipulated so as to bring the lower edge of the tool into close engagement with the inner surface of the casing 1 and pry out an object leaning over towards or even against it. When this has been accomplished, the tool is lowered further until the upper end of the sucker rod or other object is well within the object-engaging chamber 14. This, as explained, results in more or less of a contraction of the upper portion of the tool depending upon the size of the end of the sucker rod 2. The pivotal action of slips 3 about fulcrum ring 4 may be readily appreciated upon comparison of their positions shown in Figs. 1, 2 and 3 taken in order.

As soon as sucker rod 2 is well within chamber 14, rod 9 is elevated by any suitable means, either manually actuated or power driven. This results in head 10 again engaging the inwardly projecting ridges 8 of slips 3, the upper portions of slips 3 thus being forced outwardly by reason of the shape of head 10, and the lower portions of slips 3 being forced inwardly to contract chamber 14 and bring the serrated faces of the slips into firm gripping engagement with the upper portion of sucker rod 2 (see Fig. 3). Practically any desired force may then be exerted upwardly on rod 9 to remove sucker rod 2, the more power used the firmer the grip of the tool on the sucker rod will become, due to the tendency of head 10 to expand the upper part of the tool and contract the lower part thereof. In practical tests with a tool of substantially the same size and construction as that shown in the drawings, the tool has successfully lifted and held suspended a ton for an hour without showing any effects of the strain.

If for any reason it should be necessary to disassemble the parts of the tool, as for instance to replace a worn slip, this is provided for as shown in Fig. 4. Slips 3, which as stated are segmental in form, are of such a size and such a curvature externally that even when their adjacent vertical edges are brought together, they cannot be removed upwardly through fulcrum ring 4. Pro-

- vision is made, however, for removing any one of them downwardly through ring 4 after which the others may be removed in either direction. This is accomplished by 5 giving the exterior of each slip at the upper edge of its groove 5 a curvature which will just permit a selected slip to be removed downwardly through fulcrum ring 4 when the other slips are positioned so that their 10 adjacent vertical edges are abutting throughout their lengths and ring 4 is in close engagement with the inner wall of the groove 5 of these slips. This is shown in dot-and-dash lines in Fig. 4. Upon removal of one 15 slip, it is obvious that the others may then be removed readily. To reassemble the tool parts, the operations just described are carried out in the reverse order.
- In Fig. 6 the same invention is shown 20 embodied in a casing spear. In this figure the spear is shown in operative or gripping engagement with the casing 21 which it is desired to pull from the well. It will be noted that the principle of operation of the 25 slips 22, fulcrum ring 23, rod 24 and its head 25 is the same as that of the corresponding parts of the fishing tool of Figs. 1 to 5. Each slip 22 has inner inclined faces 26 and 27 forming a ridge 28 for engagement 30 with head 25 on rod 24 and an inner horizontal rib 29 to limit the downward movement of head 25 within the tool.
- The portion of the spear above fulcrum ring 23 is substantially cylindrical when not 35 in operative engagement with the casing. The external upper portion of each slip 22 above its groove 30 is provided with serrations 31 for engagement with the interior of the casing. Below its groove 30, each slip 40 22 tapers slightly downwardly to prevent jamming or binding of the spear when being lowered within the casing. The lower end of each slip 22 is inturned to form a segmental flange 32 having an arc-shaped notch 45 on its inner edge. The three arc-shaped notches in slips 22 co-operate to form an annular opening 33 in the lower end of the tool through which extends a grip-releasing member 34.
- 50 The body of member 34 tapers gradually upwardly and at its upper end has a flange 35 which rests on the upper faces of flange 32 of slips 22 to support member 34 in the lower end of the tool. The lower end of member 34 is also formed with a flange 36 to provide a larger bearing surface for a purpose hereinafter explained and to prevent member 34 from being elevated entirely within the tool during its use.
- 55 Assuming that it is desired to remove casing 21 from a well, this is done by lowering the spear into the casing by means of rod 24. During the lowering operation the spear will not operatively engage with the casing.
- 60 If during this operation, serrations 31 drag along the inner surface of the casing, this will only result in the upper portions of slips 22 swinging inwardly on fulcrum ring 23 causing a corresponding outward swinging movement of the lower portions thereof. 70 The lower portions of slip 22 taper downwardly, however, and thus there is nothing to interfere with ready lowering of the spear within the casing.
- When the tool has reached a desired point 75 in the casing, rod 24 is elevated which immediately causes the upper portion of the tool to expand and force serrations 31 into firm engagement with the inner surface of the casing 21, preliminary to elevating the 80 casing. At this point it may be mentioned that the taper of the body of grip-releasing member 34 is such as not to interfere with the inward swinging movement of the lower ends of slips 22. This appears clearly in 85 Fig. 6.
- If it is desired, either before or while they are in operative engagement, to remove the spear without the casing, this may be accomplished by first lowering rod 24 and 90 the attached spear until the lower end of member 34 comes into contact with the bottom of the well. This causes member 34 to be forced upwardly between slips 22 and spread the lower ends thereof apart by 95 reason of the tapered form of the body of member 34. As the lower portions of slips 22 are spread open, fulcrum ring 23 causes the upper portions of the slips to move together radially and release the grip of the 100 spear from the casing. Member 34 is retained in its last-mentioned position by friction and the spear may be removed readily from the casing by rod 24.
- Numerous changes in the structure illustrated and described may be made without departing from the spirit of this invention except as it may be limited by the attached 105 claims.
- What is claimed is:
1. In a grapple, the combination of a plurality of slips each having a transverse groove formed in the exterior surface thereof; a fulcrum ring loosely mounted in said grooves and serving to maintain said slips 115 in assembled relation; a relatively movable head located between the slips for engagement therewith only above the fulcrum ring to swing the upper portion of each of the slips outwardly about said ring as a center, 120 each of said slips having a portion adapted, upon said swinging movement of the slips, to engage an object to be lifted; and suspension means for said head.
  2. In a grapple, the combination of a 125 plurality of slips; a ring on which said slips are pivotally mounted intermediate their extremities for vertical swinging movement of said extremities toward and from each other; movable means located between 130

the slips for spreading apart the upper extremities thereof, said slips each having a portion adapted, upon said spreading apart of the extremities of the slips, to engage an object to be lifted; and suspension means for said movable means.

3. In a grapple, the combination of a plurality of upright slips; a ring on which said slips are pivotally mounted intermediate their extremities; relatively movable means located between said slips for causing expansion of the upper portion of the grapple and contraction of the lower portion thereof, said slips each being provided with a portion adapted, upon expansion and contraction of said portions of the grapple, to engage an object to be lifted; and suspension means for said relatively movable means.

20 4. A grapple such as is set forth in claim 3, in which the relatively movable means have a universal connection with the slips.

5. A grapple comprising a plurality of upright slips each having a transverse groove in the exterior surface thereof; a continuous ring surrounding the slips and loosely mounted in said grooves; suspension means; and means, on the lower end of said suspension means, located between the slips for engagement therewith to move said slips into engagement with an object to be lifted, said parts being so proportioned and arranged as to permit disassembly of the grapple only by first removing one of said slips.

35 6. A tool of the character described comprising a plurality of upright, segmental slips; a ring on which said slips are pivotally mounted for vertical swinging movement towards and from each other; means disposed between said slips for engagement therewith to cause said swinging movement, said slips each having an inner, lower portion adapted, upon said swinging movement, to engage an object to be lifted; and

suspension means for said slip-engaging means, the lower portions of the adjacent slips coacting with each other to present an opening between the slips for the entrance of the object to be lifted.

7. In a grapple, the combination of a plurality of upright, segmental slips, each of which has a transverse groove in its outer surface intermediate its ends; a fulcrum ring surrounding the slips and loosely mounted in said grooves, the upper portion of each of said slips being formed with an inwardly projecting portion on its inner face; and an upright suspension member having a downwardly flaring head on its lower end, said head being movably located between said slips above the fulcrum ring for coaction with said inwardly projecting portions of the slips to swing the upper portions of the slips radially outward and the lower portions thereof radially inward, the lower portions of the slips having portions on their inner faces adapted for gripping engagement with an object to be lifted.

8. A grapple of the character described comprising a plurality of upright, segmental slips having transverse grooves in their outer faces intermediate their ends and object-engaging surfaces on their lower, inner faces; a fulcrum ring surrounding the slips and loosely disposed in said grooves to retain the slips in assembled relation; actuating means disposed between said slips and adapted, upon relative longitudinal movement of said means and the slips, to move said slips radially away from each other at their upper ends and radially towards each other at their lower ends; and suspension means for said actuating means.

In testimony whereof I have signed my name to this specification.

HARRY S. GORE.
